PORTABLE DUPLEX PERFORATOR.

Hjalmar A. Swanson, Chicago, Ill., assignor to
 Cummins Perforator Company, Chicago, Ill., a
 corporation of Illinois

Application December 24, 1938, Serial No. 247,612

7 Claims. (Cl. 101—20)

The invention relates to perforating machines and has reference more particularly to a perforating machine of the portable duplex type which will receipt stub bills such as tax bills and those of public service and utility companies by perforating the date of payment and other data in said bills.

An object of the invention is to provide a portable perforator which will be power driven by means of a continuously running electric motor and wherein novel trip means will be actuated automatically by the insertion of a bill or the like for causing operation of the perforator head to produce a punching operation on said bill.

Another object resides in the provision of automatic trip means for operatively connecting the continuously running electric motor with the perforator head and which will be combined in a novel manner with manually actuated trip means for accomplishing the same purpose. When the hand operated trip is intended for regular use it is not necessary nor advisable to include the automatic trip means, but when the latter is to be used regularly, then the invention contemplates the combination therewith of the hand trip for possible emergencies.

A further object resides in the provision of a perforator of the type described which will embody novel trip means for producing a perforating operation and which will permit only one operation of the perforator head for each actuation of said trip means.

Another object resides in the provision of improved clutch means normally held in latched position to permit the motor to rotate independently but which when released by the trip means will operatively connect the motor with said perforator head for a complete revolution of said clutching means so that following one cycle, as above outlined, the clutch will automatically latch and remain in this position until again tripped.

A further object is to provide a portable duplex perforator having a hand operated stub ejector which will remove the stub bills from the die opening when the stubs are too small to be conveniently removed by hand.

Another object of the invention is to provide a portable duplex perforator that can be unlocked by the insertion of a key in said machine, permitting operation thereof, and which will automatically lock again when the key is withdrawn. In accordance with the invention, said key has indicia perforated therein which will cause an identifying number to be perforated in the bill and stub portion of the same during the

operation of receipting the bill, whereby the employee receipting the bill and receiving the money can be readily identified through the indicia of his respective key.

5 A further object is to provide a portable duplex perforator embodying a continuously running electric motor and which will provide a signal light readily visible to the operator of the machine for indicating that the motor is in operation.

10 With these and various other objects in view, the invention may consist of certain novel features of construction and operation, as will be more fully described and particularly pointed out in the specification, drawings and claims appended hereto.

In the drawings which illustrate an embodiment of the invention and wherein like reference characters are used to designate like parts—

20 Figure 1 is a side elevational view of the improved portable duplex perforator of the invention;

Figure 2 is a top plan view of the perforator shown in Figure 1;

25 Figure 3 is a fragmentary elevational view, parts being shown in section, of the combined automatic and manual tripping means for releasing the clutch to produce a perforating operation;

30 Figure 4 is a fragmentary elevational view illustrating the locking means for locking the machine against operation; and

Figure 5 is a plan view of the key which when inserted in the present machine will release the locking means.

35 The perforator selected for illustration in the drawings is housed within a frame including a base member 10 having side walls 11 and 12, a rear wall 13 and a front wall 14. A cover 15 of the removable type and having depending front and rear portions 16 and 17, respectively, encloses the oscillating perforator head of the present machine and completes the structure of the frame. A die block 18, suitably supported by

40 the frame adjacent the front wall 14 thereof provides a paper supporting surface on which is placed the bill or the like to be perforated. Suitably supported in spaced relation above the die block 18 are a pair of blocks 20 each supporting 45 in vertical position sets of punches 21 and 22 for perforating a bill and the stub portion thereof with the date of payment and other information. The perforator head, designated in its entirety by numeral 23, locates over the punches 22 two sets of coaxial, rotatably adjustable punch con-

trol members 24 which select the punches to be actuated and produce actuation thereof when the perforator head is oscillated. The keys 25, which must be inserted in the perforator head to release the machine for operation, are each located over a set of punches 21, and said keys control the actuation of these punches for perforating a number on the bill and stub portion thereof which will identify the particular employee operating the perforating machine.

The perforator head 23 consists of elongated side members 26 and 27, suitably connected together at the forward end by means 28 which rotatably support the control members 24 and which pivotally connect with the side walls 11 and 12 at the rear end through the horizontally disposed transverse shaft 30. In order to strengthen the walls at this point for pivotally supporting the perforator head, portions 31 are suitably secured as by welding to the outside surface of each side wall and said member at its upper end is perforated for receiving an end of the shaft 30. Each side member 26 and 27 is provided with a boss 32 at its rear and said bossed part of the member is located to the outside of its respective side wall but inside of its portion 31. The side walls therefore pivotally support and also act as guides for the members 26 and 27, confining their movement and that of the perforator head to a true vertical plane. A link 33 pivotally connects with each side member as at 34, directly to the rear of the control members 24. Said links at their opposite ends connect with an eccentric 35 provided by the operating shaft 36, suitably journaled by bearings 37 and which extends through the side walls 11 and 12. The gear 38, fixed to said shaft meshes with the worm gear 39 on the motor shaft 40 of the electric motor 41. The perforator head 23 is accordingly oscillated by means of said links 33 when rotation is imparted to shaft 36 through operation of the electric motor 41.

The present invention contemplates a continuously running electric motor normally disconnected from shaft 36 through clutch means to be presently described and which clutch means may be tripped automatically by the insertion of a bill or the like in the machine to result in a perforating operation on the same.

The gear 38, as best shown in Figure 3, is provided with a hub 42 recessed for receiving the structure of the clutch which may be of any conventional type for operatively connecting the electric motor and said operating shaft when the clutch is tripped and which will readily disconnect the parts and maintain this relation when latched. The clutch illustrated in Figure 3 essentially consists of a body member 43 keyed to the operating shaft 36 so as to rotate therewith and which is formed with a plurality of recesses 44 of substantially triangular shape for receiving a roller 45 backed by a coil spring 46. Mounted so as to freely rotate on the operating shaft 36 are a pair of plate members 47, a member being positioned on each side of the body portion and said members being connected by the transverse studs 48. The body portion is provided with notches of substantially square shape, receiving the transverse studs 48 and which therefore have limited movement with respect to the body portion. Rollers 45 are carried in recesses 50 in the plate members and since the plate members may have limited movement with respect to the body portion, it will be seen that relative movement in one direction will free the rollers with respect

to the interior surface of the hub 42, whereas, relative movement in an opposite direction will force the rollers into clutching relation with said hub portion. The plate member 47 located exteriorly of the hub portion is provided with a notch 51 adapted to receive the trip lever 52 which is normally in latched position, holding the plate members against rotation. Therefore, the shaft 36 is also held against rotation although gear 38 and its hub portion may freely rotate. When the trip lever is withdrawn the springs 46 force their respective rollers into such wedging engagement with the internal periphery of the hub portion as to cause shaft 36 to be driven by the motor 41 and to produce oscillating movement of the perforator head.

The structure for tripping said clutch will now be described. The tripping lever 52, pivotally supported at 53 from the side wall 12, has projecting upwardly therefrom an actuating arm 54. Any movement imparted to said arm will be transmitted to said tripping lever. The upper end of the actuating arm 54 extends vertically above and is adapted to contact the horizontally disposed lever 55, clearly shown in Figure 2, pivoted at 56 to the side wall 11 and at its opposite end extending a short distance beyond side wall 12. On the outside of the wall 12 immediately below lever 55 there is slidably supported a horizontal bar 58 which extends toward the front wall 14 of the machine. Member 57 supports said front end of the bar and the part 58 supports the rear end. Said bar is yieldingly biased in a direction toward the front wall of the perforator by coil spring 60. For automatic operation a member 61 is suitably fixed to the bar 58 at the forward end thereof and which is provided with a portion 62 aligned with the throat or passage of the machine within which a bill or the like to be perforated is inserted. Partial insertion of the bill will result in its leading edge coming in contact with portion 62 of member 61 and continued insertion of the bill will move said member and bar 58 in a direction rearwardly against the tension of spring 60. A latching lever 63 is pivoted at 64 to the horizontal bar and said lever is formed on its undersurface with a latching recess 65 adapted to have latching engagement with the end of lever 55 extending beyond side wall 12. Said lever 63 also provides a depending arm 66 adapted to contact an adjustable stop 67 as a result of rearward movement of the horizontal bar 58. Figure 3 illustrates the position of the parts after contact has taken place between depending arm 66 and said stop 67. It will be noted that the latching lever has been rotated to a slight extent on its pivot 64 in a counter-clockwise direction and as a result the latched end of lever 55 is partly released. Movement of bar 58 in a rearward direction sufficient to produce rocking movement of the latching lever to this extent will have moved the horizontally disposed lever 55, actuating arm 54, and the tripping lever 52 to release the clutch to produce a perforating operation. This perforating operation is the result of rotation of shaft 36, actuation of the links 33 to cause downward movement of the perforator head, and therefore actuation of the proper punches to perforate the bill or the like inserted within the die opening for the purpose.

For manually tripping the clutch to cause a perforating operation to take place the invention provides a lever 70 adapted to be finger operated and pivotally secured at 71 to wall 12.

The upper end of said lever is provided with a part 12 readily accessible to the operator of the machine. Link 73 connects said lever to the pivoted lever 74, also supported from wall 12 at 15. The link 73 and lever 74 are connected by the coil spring 76 which tends to draw the parts together and as a result maintains levers 10 and 14 in a substantially vertical position. A strip of flat spring steel 77 is suitably fixed at 78 to lever 74 and positioned vertically thereby so as to have contact with member 61. The part 80 fixed to said member and to the bar 56 provides a guide for the upper end of said part 77 which as a result of its contact with member 61 will produce actuation thereof and movement of the bar 15 56 when the lever 10 is manually actuated by the operator. Bar 56 will produce movement of latching lever 63, lever 55, arm 54 and tripping lever 52 to release the clutching elements so as to cause a perforating operation to take place. Also movement of said bar will cause the latching lever to pivot in a counter-clockwise direction to eventually release lever 55, whereupon said lever, bar 54 and tripping lever 52 will be free to again latch the clutch following one revolution of the operating shaft 36. It will be observed that the actuating arm 54 is yieldingly held to cause latching of the clutch by the spring 68.

Movement of the lever 10, imparted thereto by the operator for manually tripping the clutch, is transmitted to the bar 56 through the strip of spring steel 77. This is necessary since the actuating bar 56 may be locked against movement and when this is the case the strip 77 readily yields and prevents damage to the tripping mechanism. As regards part 61, providing the automatic trip, this is fixedly secured to the operating bar 56 since the same can be actuated only by insertion of a bill or similar sheet of paper in the machine. When the parts are locked against movement the bill can be inserted in the machine until it contacts portion 62. It is impossible for the operator to apply sufficient pressure through the thin sheet of paper such as the bill or the like to damage the tripping mechanism.

In the event the operator holds the lever 10 in depressed position, the present mechanism will allow the shaft 36 to rotate for one complete revolution only. This is the result of the pivoted latching lever 63 which by its counter-clockwise pivotal movement releases levers 55, bar 54 and tripping lever 52 so that they are yieldingly returned to a position where latching of the clutch will take place following one revolution. In order to insure that bar 56 will be moved rearwardly to cause pivoting of the latching lever 63, so as to release engagement with lever 55, the invention provides an arm 81 pivoted at 82 and operatively connecting by means of link 83 with the upright link 33 connecting with the perforator head. The lower end of link 33 is in effect oscillated as a result of its connection with eccentric 35. Movement of the lower end of link 33 is transmitted to arm 81 and said arm is caused to engage pin 84 on the operating bar 56 and move said bar in a direction rearwardly. For every release of the clutching elements to produce a perforating operation arm 81 will be brought into contact with pin 84 and the operating bar 56 will be automatically moved rearwardly to the extent where full pivotal movement of latching lever 63 will take place. Full pivoted movement of this lever releases lever 55 and thus arm 54 so that these parts are free to

return and again latch the clutch following one revolution of the operating shaft.

As previously brought out, the keys 25 are inserted in the present perforator in order to release the same for operation and said keys also control the punches 21 to perforate a number on the bill and stub portion thereof for identifying the particular employee receiving the bill. Said keys release locking means in the form of a latching arm 85, Figure 4, having a downwardly bent end portion 86. The shaft 34, which pivotally connects links 33 with the side members of the perforator head, provides journalling means for the U-shaped frame 87. The latching arm 85 is suitably secured to one side portion of said frame, as clearly shown in Figure 2, and the pin 88 projects outwardly from the other side portion of the frame.

Referring to Figure 4, it will be seen that the upwardly bent end 90 of lever 91 is normally in contact with said pin and therefore any pivoting movement of the lever will produce oscillation of frame 87 and also of latching arm 85. Lever 91 is pivotally secured at 92 to side wall 11 of the machine and carries a pin 93 projecting from that side of the lever directed toward the control members 24. This pin is adapted to have contact with the leading edge of a key 25 when inserted in the machine and for the purpose said leading edge of the key is bevelled as at 94. When the key is inserted the pin 93 will ride up said bevelled edge 94 and upward movement is thereby imparted to lever 91. Similar movement of the frame 87 results and likewise the bent end portion 86 is elevated. As clearly illustrated in Figure 1, said elevation of the bent end 86 will free the actuating arm 54. The tripping mechanism of the perforator may now be actuated either automatically or manually for perforating a bill or the like. However, when the key 25 is withdrawn, lever 91 will drop and corresponding downward movement of frame 87 and arm 85 will latch the actuating arm 54, locking the same against movement. The tripping lever 52 is thereby held in its notch 51 and although the electric motor of the perforating machine may be set in motion the tripping mechanism is inoperative to release the clutch.

As shown in Figure 5, each key 25 is provided with perforations 95 which, however, leave a solid portion bounded by said perforations forming an identifying number. Certain of the punches 21 are actuated by the solid portion of the key to perforate the bill, reproducing an identifying number therein. Accordingly, when the keys have been inserted in the perforator to release the same for operation the number of the particular employee is perforated in all bills received by him. The company is therefore able to identify the employee in the event of falsification of the records and appropriation of money for his own use.

The perforating head 23 at 96 pivotally connects with link 97 which in turn is fastened to the upper cutting blade 98. Said upper blade is pivotally supported at 99 by the punch blocks 20 and has coaction with a stationary lower cutting blade 100 for the purpose of severing the stub portion of the bill from the main portion thereof. In transactions such as receiving bills for utility companies the stub portion is retained by the company and the main portion is returned to the customer. It often happens that the stub portions are too small to be conveniently removed by hand. In this event, the stub ejector 101 may

be actuated through its handle portion 102 by drawing the same forwardly. The rear upwardly bent end of said stub ejector projects a slight distance above the paper supporting surface formed by the die block 18 and the stub portion is thereby ejected from the die opening. The stub ejector 101 is yieldingly held by coil spring 103 so that movement of the same forwardly for ejecting the stub bill takes place against the tension of said spring. A receptacle 104, having a handle 105, is suitably mounted in the frame structure of the present perforator adjacent the front wall 14 thereof for the purpose of collecting the punchings which drop from the die openings in the die block 18.

The insertion of a sheet such as a bill or the like in the present perforating machine will automatically actuate the trip mechanism by moving the horizontal bar 56 rearwardly. Initial movement of this bar will be transmitted to the trip lever 52 whereby the clutch is released and a perforating operation takes place as a result of rotation of the operating shaft 36. One complete revolution of this shaft will produce an up and down oscillatory movement of the perforator head, producing actuation of the punches on its down movement, and as a result of its up movement the head will be located in initial position. Due to the pivoted latching lever 63 the latching means for the clutch is released automatically by continued rearward movement of the horizontal bar. If said movement is not sufficient, which happens when the bill is not inserted in the machine far enough, the arm 81 will be caused to strike pin 84 on the bar, moving the same rearwardly to insure full pivotal movement of said lever. Full pivotal movement of the same will free lever 55 and arm 54 so that these parts will return under the tension exerted by spring 68 to again latch the clutch following one revolution of the operating shaft. In the present perforator only one perforating operation will take place for each actuation of the trip mechanism and this is the case irrespective of whether the trip mechanism is actuated automatically by the insertion of a sheet in the machine or manually by depressing the lever 70.

The numeral 106 indicates a lock in the form of a switch for the electric motor 41 and which switch must be closed by the operator before the perforating machine can be used. The lock is adapted to receive a key, which may be turned after insertion in the lock for closing the switch. When the electric circuit to the motor is closed through said switch the bulb 107, positioned on cover 15, will light and the same will remain lighted during the time the motor is in operation. Since the present perforator embodies a continuously running electric motor a visible indicator of this type is desirable.

The invention is not to be limited to or by details of construction of the particular embodiment thereof illustrated by the drawings, as various forms of the device will of course be apparent to those skilled in the art without departing from the spirit of the invention or the scope of the claims.

What is claimed is:

1. In a duplex perforating machine, in combination, a frame, an oscillatable perforator head 70 pivotally supported by said frame and which when oscillated effects a perforating operation, an electric motor having a drive shaft adapted to rotate constantly while the perforating machine is in use, an operating shaft journalled by

said frame, links connecting said shaft with said perforator head for oscillating the same, a clutch interposed between said operating shaft and said drive shaft, latching means yieldingly biased in a direction to hold said clutch in latched position whereby said operating shaft remains at rest, trip mechanism for releasing said latching means including a horizontally movable bar supported by the frame and a pivoted lever carried by the bar and having releasable engagement with said latching means, said bar when moved in one direction causing actuation of said latching means to release the clutch and thereafter automatically causing said pivoted lever to release its engagement with the latching means so that the same is free to again latch the clutch following a complete revolution, and means connecting with said links and receiving actuation therefrom for moving said horizontal bar to insure release of said latching means by the pivoted lever, whereby one actuation of the trip mechanism will produce only one perforating operation.

2. In a perforating machine, an oscillatable perforator head which when oscillated effects a perforating operation, means pivotally supporting said perforator head, an electric motor having a drive shaft adapted to rotate constantly while the perforating machine is in use, an operating shaft having connection with said perforator head for oscillating the same, a clutch interposed between said operating shaft and said drive shaft, latching means yieldingly biased in a direction to hold said clutch in clutched position whereby said operating shaft remains at rest, and trip mechanism for releasing said latching means including a horizontally movable bar and a pivoted lever carried by said bar and having releasable engagement with said latching means, said bar when moved a predetermined extent in one direction causing actuation of said latching means to release the clutch, and means effecting limited rotation of the pivoted lever as a result of further movement of said bar in the same direction, whereby the lever is caused to release its engagement with the latching means so that the latching means is free to again latch the clutch following a complete revolution.

3. In a perforating machine, an oscillatable perforator head which when oscillated effects a perforating operation, means pivotally supporting said perforator head, an electric motor having a drive shaft adapted to rotate constantly while the perforating machine is in use, an operating shaft having connection with said perforator head for oscillating the same, a clutch interposed between said operating shaft and said drive shaft, latching means yieldingly biased in a direction to hold said clutch in clutched position whereby said operating shaft remains at rest, trip mechanism for releasing said latching means, said mechanism including a horizontally movable bar and a lever pivotally carried by the bar at one end thereof and having releasable engagement with said latching means, said bar when moved a predetermined extent in one direction causing actuation of the latching means to release the clutch, and means effecting limited rotation of the pivoted lever as a result of further movement of said bar in the same direction whereby the lever is caused to release its engagement with the latching means so that the same is free to again latch the clutch following a complete revolution, and other means receiving actuation simultaneously with oscillating movement of the perforator head and operative to move said horizontal bar its full

extent to insure release of said latching means by the pivoted lever, whereby one actuation of the trip mechanism will produce only one perforating operation.

4. In a perforating machine, an oscillatable perforator head which when oscillated effects a perforating operation, an electric motor having a drive shaft adapted to rotate constantly while the perforating machine is in use, mechanism including a clutch for connecting said drive shaft with said head for oscillating the same, latching means yieldingly biased in a direction to hold said clutch in clutched position whereby said perforator head remains at rest, trip mechanism for releasing said latching means including a movable bar having releasable connection with the latching means, said connection being constructed and arranged whereby initial movement of the bar actuates the latching means to release the clutch and further movement effects disconnection of the latching means with respect to the bar so that said latching means is free to again latch the clutch following a complete revolution, and means receiving actuation simultaneously with oscillating movement of the perforator head and operative to move said bar its full extent to insure disconnection of the latching means with respect to said bar, whereby one actuation of the trip mechanism will produce only one perforating operation.

5. In a perforating machine, in combination, a frame, an oscillatable perforator head supported by said frame, an electric motor having a drive shaft adapted to rotate constantly while the perforating machine is in use, mechanism including a clutch for connecting said drive shaft with said head for oscillating the same, latching means yieldingly biased in a direction to hold the clutch in latched position to render the mechanism inoperative, trip means for actuating the latching means to release the clutch, said means including a member having releasable engagement with the latching means and a movable bar carrying said member, said bar when moved a predetermined extent in one direction causing actuation of the latching means through said member to render

the clutch operative, and means effecting relative movement of the member as a result of further movement of the bar in the same direction to release the latching means, whereby said latching means is free to again latch the clutch following a complete revolution.

6. In a perforating machine, the combination with a plurality of punches, of an oscillatable head for actuating said punches, a drive shaft for oscillating said head, mechanism including a clutch for operatively connecting said drive shaft with said head, latching means for latching the clutch for rendering the mechanism inoperative, means carried by said oscillatable head and having an operative position for locking the latching means in latched position, a key for insertion in said head to render the locking means ineffective, said key upon insertion having a position over certain punches and being operative to depress certain of said punches when the head is oscillated, and trip mechanism having association with said latching means for tripping the latching means to release the clutch provided the said means is not locked.
7. In a perforating machine, the combination with a plurality of punches supported by a stationary base, of an oscillatable head pivoted to said base for actuating said punches, an electric motor located within the base below said head and having a drive shaft for oscillating the head, mechanism including a clutch for operatively connecting said drive shaft with said head, latching means for latching the clutch to render the mechanism inoperative, means carried by the oscillatable head for locking the latching means in latching position, a key for insertion in said head to render the locking means ineffective, said key upon insertion having a position over certain punches and being operative to depress certain of said punches when the head is oscillated, and trip mechanism supported by the station base and having association with said latching means to release the clutch provided the means is not locked.

HJALMAR A. SWANSON.

Patent No. 2,248,136.

CERTIFICATE OF CORRECTION.

July 8, 1941.

HJALMAR A. SWANSON.

It is hereby certified that error appears in the printed specification of the above numbered patent requiring correction as follows: Page 5, second column, line 41, claim 7, for the word "station" read --stationary--; line 42, same claim, after "means" insert --for tripping the latching means--; and that the said Letters Patent should be read with this correction therein that the same may conform to the record of the case in the Patent Office.

Signed and sealed this 26th day of August, A. D. 1941.

(Seal)

Henry Van Arsdale,
Acting Commissioner of Patents.
